SPORTSMAN'S MITTEN

**George J. La Londe and Allen Jewer,
Detroit, Mich.**

Application August 24, 1945, Serial No. 612,500

3 Claims. (Cl. 2—158)

This invention relates to sportsman's mitten, the object being to provide a mitten of a new and improved structure for use of hunters, fishermen and "out of doors" workmen, in which there is provided a slot transversely of the mitten at about the center of the palm, the meeting edges of the slot being provided with separate metal strips of the well known zipper type metallically secured together at opposite ends to provide a metal binding for the edges as well as the ends of the slot and preventing the tearing of the fabric or material wear at the bound edges of the slot.

A further object and feature of the invention is to provide a mitten with the zipper bound slot and a flap beneath the zipper on the side of the slot toward the tip of the mitten and a flap on the opposite side of the slot extending over the said slot and zipper strips to protect the hand of the user by preventing snow and moisture from entering the slot and further to permit handling of objects without contact thereof with the metal strips.

These several features and objects of the invention involved in our improved mitten are herein-after more fully described and claimed and the preferred form of construction of a mitten embodying our invention is shown in the accompanying drawings in which

Fig. 1 is a plan view of the mitten showing the outer flap overlying the slot and zipper structure.

Fig. 2 is a plan view of a mitten with the upper flap and thumb portion of the mitten turned backward to expose the slot and zipper strips.

Fig. 3 is a section taken on line 3-3 of Fig. 1.
Fig. 4 is a view in elevation taken on line 4-4.

The mitten of our invention is particularly

adaptable for use of hunters, fishermen or "out of doors" workmen who in the winter time desire to protect the hands from the cold and yet to readily permit the fingers of the hands to be projected through a slot provided transversely of the palm to use in operating the trigger of a gun or the reel of a fishing rod or other like purposes where the workman is using tools in cold weather which may be carried in the hand with the slot closed but when operated or utilized requires the use of the bare fingers.

In the preferred form of construction of a mitten embodying our invention, the mitten may be of any desired fabric or may be provided with leather palm or made wholly of leather, it not being of importance to this invention what material is used in the making of the mitten, whether of knitted or woven fabric or of leather, but

rather to provide a mitten of a structural form having the facilities and functions as above outlined and while I have used the term "fabric" herein as being the material of which the mitten is made it is to be understood that any desired character of material may be used.

Whatever the material used, the mitten is provided with a slot indicated at 1 in approximately the center of the palm of the mitten 2. This slot has its opposite edges provided with complementary zipper strips 3 and 4 which are metalically secured together at one end by the U-shaped metal piece 5 and at the opposite end by a metal element. The usual slide 7 is movable from the metal element or binder 6 toward the opposite end of the zipper strips to close the slot or in the opposite direction to open the slot. When the slot is opened obviously the fingers of the user may be projected therethrough to grasp an implement or a gun or, if used in driving an automobile, to grasp the steering wheel firmly with the fingers and, when not required for any such use, the strip may be closed by moving the slide to the left toward the element 5. The outer flap 8 may then be turned thereover to the position shown in Fig. 1 covering the slot and preventing ingress of snow and moisture to the interior of the mitten.

When projected through the slot provided by the opened zipper strips, the fingers of the user would, if not otherwise prevented, be subjected to scratching. Therefore, in its preferred form, the mitten is provided with an inner as well as an outer flap.

35 This will be more clearly understood from Fig. 3 in which the face of the material 2 in the palm has the zipper strip 3 attached thereto by means of the fabric 9 to which said strip is secured and this fabric is secured at one edge to an inner flap 40 10 stitched in position by the sewing of an edge of the flap 10 and fabric 9 of the zipper strip 3 to the body of the fabric of the mitten at the upper or outer edge of the slot. This flap 10 extends at its free edge toward the wrist 2a to beyond the 45 slot and covers the opposed zipper strip 4. This zipper strip 4 also has a fabric portion 11 stitched to the fabric of the palm of the mitten and this fabric portion 11 extends over and normally covers the slot and zipper elements. In this relationship of the parts, the mitten may be used in the ordinary manner as occasion may demand for handling various articles, such as a gun, fishing rod or other implement or device. In such relationship and normal use, the slot is closed by the 50 movement of the slide to the left from the position

shown in Fig. 2 as will be readily understood and the zipper strips are covered to prevent marring or scratching the surface of the article being handled.

When the mitten is to be used in handling of a gun, for instance, or in other use where part of the time the fingers are not required for use and at other times are required to be projected, the zipper may be opened by movement of the slide toward the right hand end of the slot thus enabling the user to project the fingers through the slot. In thus projecting the fingers, the free edge of the inner flap 10 is automatically forced outwardly through the slot thus covering the upper or outer zipper 2 which without the flap would otherwise be engaged by the back of the hand. When the fingers are withdrawn from the slot to the interior of the mitten both flaps normally tend to cover the slot.

It is therefore to be realized that where the user occasionally requires use of the fingers in the grasping or manipulation of an element, such as a fishing reel, the trigger of a gun or other element or apparatus, the mitten is worn with the slot open to enable the fingers to be readily projected through the slot for a required use and then withdrawn from the slot until again required to be projected. The hands of the user are thus at all times protected from cold except the period during which the fingers may be projected from the slot. The mitten may be used with the slot closed for any considerable period of time in which the fingers are not required to be projected and under such condition the zipper may be closed or may be left open as the flaps cover the slot and by positioning the slot transversely of the palm practically centrally thereof, the zipper lies within the palm and is not detrimental or materially noticeable in grasping any object that does not require the use of the fingers specifically. For instance, in the carrying of a gun to and from a hunting area the zippers may be closed and the gun handled readily as the zipper lies in the portion of the hand that would not interfere with the movement of the fingers as a whole in grasping an object. The feature of the invention, therefore, resides in the provision of a slot transversely of the palm of the mitten on a line lying within the palm of the hand and the slot is normally closed by the opposed flaps. The zipper 3 toward the tip of the mitten lies closely adjacent to the mitten fabric forming the outer edge of the slot and thus to a degree prevents wear of the fabric by frequent movement of the fingers through the slot and, when the zipper strips are in open position, the inner flap 10 covers the outer zipper strip and protects the hand of the user.

It is pointed out, however, that the invention is not confined to the use of an inner flap, such as the flap 10 shown, as the mitten is usable without such a flap. However the outer flap 8 is considered essential otherwise snow and moisture might pass into the interior of the mitten even though the zipper strips be closed. The invention broadly, therefore, exists in the provision of the slot having the opposed zipper strips at the edges thereof and the metallic elements at the opposite ends of the slot located transversely and substantially centrally of the palm of the hand of the user so that in gripping an object the zipper strips do

not interfere with the handling of the object by the hand covered by the mitten.

It is further pointed out that the outer flap 8 is of considerable width on a line longitudinally of the palm and is preferably rounded at the ends and preferably is an integral part of the portion of the mitt towards the wrist. The flap, due to its not being secured at its ends to the mitten fabric, is thus readily turned either to cover or uncover the zipper strips.

From the foregoing description it is believed evident that the various objects and novel features of the invention are attained by the structural arrangement of parts as described and that various changes may be made therein without departing from the spirit and scope of the invention as set forth in the appended claims.

Having thus fully described our invention, its utility and mode of construction, what we claim and desire to secure by Letters Patent of the United States is:

1. A mitten having a front and a back of suitable material attached together at peripheral edges, said front having a transverse opening substantially centrally of the palm providing edge portions in the same plane, a zipper strip on each edge of the opening metallically secured together at the opposite ends, a slide for opening or closing the zipper strips, and a flap on each side of said opening normally overlying the said opening and zipper strips.

2. A mitten having a front and a back attached together, the front being in two parts providing a transverse opening substantially centrally of the palm and providing oppositely extending flap portions covering the opening, a zipper strip at the base of each of the opposed faces of the flaps and normally lying in parallel relation, and a slide movable across the zipper strips to open or close the same.

3. A mitten having a front and a back attached together, the front being in two parts each having a flap portion, said flap portions being in overlapping relationship and each unattached at its opposite ends to the back, a zipper strip on the outer face of the inner flap, and a complementary zipper strip on the inner face of the outer flap, the two strips normally lying in edge to edge relation in the same plane, and a slide for opening or closing the zipper strips.
